WINDOW

Hamilton T. Reynolds, Huntingdon, Pa.

Application May 15, 1933. Serial No. 671,223

22 Claims. (Cl. 20—49)

This invention relates to certain new and useful improvements in windows of that type including upper and lower vertically movable sashes and has for its object to provide, in a manner as hereinafter set forth a window with novel, simple and inexpensive attachments which will allow the upper and lower sashes to be adjusted to assume any desired angle with respect to a vertical plane and vertically movable when disposed at an angle 5 to facilitate the reaching of the outside of the sashes for any purpose whether for cleaning, painting, replacing broken lights, or for any other purpose without the danger attendant upon mounting the window-sill to reach the outside of 10 a sash.

A further object of the invention is to provide, in a manner as hereinafter set forth, a window of the type referred to with means whereby the sashes may be disposed at any desired angle with 20 respect to a vertical plane and vertically moved when so disposed relative to the window frame for opening the window to the desired extent for ventilating purposes.

A further object of the invention is to provide, 25 in a manner as hereinafter set forth, a window of the type referred to having means whereby each of the sashes thereof may be turned completely inside-out and to a vertical position for conveniently reaching the outer face of a sash, when occasion requires from the interior of a 30 room.

A further object of the invention is to provide, 35 in a manner as hereinafter set forth, a window of the type referred to including a pair of spring controlled slideable jamb sections, an upper and a lower pair of vertically movable slides arranged against said sections, a sash carried by, pivotally supported from and capable of being disposed at an angle with respect to a pair of slides, and 40 means to arrest the upper sash from pivoting with respect to its slides until the latter has been shifted vertically a part of the vertical path thereof.

A further object of the invention is to provide, 45 in a manner as hereinafter set forth, a window of the type referred to having its upper sash carrying means coacting with its pair of slides for latching it in closed position and with said means coacting with the window frame and providing when the upper slides are lowered for a part of the vertical path thereof for latching the upper sash at an angle with respect to the window 50 opening.

To the above ends and others which may hereinafter appear, the invention consists of the novel construction, combination and arrangement of

parts as hereinafter referred to and illustrated in the accompanying drawings, wherein is shown an embodiment of the invention, but it is to be understood that changes, variations and modifications may be resorted to which fall within the 60 scope of the invention as claimed.

In the drawings:

Figure 1 is a fragmentary view in front elevation of the window.

Figure 2 is a section on line 2—2 Figure 1. 65

Figure 3 is a section on line 3—3 Figure 4.

Figure 4 is a section on line 4—4 Figure 3.

Figure 5 is a sectional detail upon an enlarged scale of the upper portion of a jamb structure.

Figure 6 is a view similar to Figure 5 of the 70 lower portion of the jamb structure.

Figure 7 is a fragmentary view in section showing a sustaining element attached to a lower slide.

Figure 8 is a view similar to Figure 8 showing 75 a sustaining element connected to an upper slide.

Figure 9 is a fragmentary view in rear elevation of the window.

Figure 10 is a view similar to Figure 2 with the sash turned inside-out.

Figure 11 is a detailed view in perspective showing the upper sash in latched closed position. 80

Figure 12 is a sectional detail showing a modified arrangement of pivoting the sash to a slide.

Figure 13 is a detail in elevation, partly broken away, showing the upper sash provided with a 85 latching means corresponding to that employed in connection with the lower sash.

Figure 14 is a sectional detail illustrating a bearing means for the shiftable jamb sections. 90

Figure 15 is a vertical sectional view of the 90 window showing the sashes angularly adjusted with respect to the slides.

Figure 16 is a fragmentary view in vertical section showing a different angular position of the upper sash from that shown in Figure 15. 95

Figure 17 is a sectional plan showing the wedging of the shiftable section of the jamb structure caused by the application of pressure on the outwardly disposed end of the upper sash. 100

Figure 18 is a view showing the manner of anchoring either end of the stationary section of the jamb structure.

Figure 19 is a perspective view broken away of the stationary section of the jamb structure.

The drawings show but one side of the window. The other side will be of the same construction as that side illustrated. The drawings show but one side of each of the sashes, but the other side of each sash would be similar to that side illustrated. Associated with each sash 110

is a pair of slides. Each slide of a pair is of like construction. Each slide is formed of two portions of different widths. The portion of greatest width of a slide is of less length than the other portion and arranged at one end of the slide. The slides for the lower sash are oppositely disposed with respect to the slides of the upper sash. The portions of greatest width of the slides for the upper sash are arranged at the upper terminal parts thereof and are formed by laterally offsetting the slides outwardly as hereinafter referred to and indicated. The portions of greatest width of the slides for the lower sash are arranged at the upper terminal parts thereof and are formed by laterally offsetting the lower slides outwardly as hereinafter referred to and indicated. The drawings show but one slide of each pair.

In the drawings, 1 indicates the window-sill, 2 the top frame member, 3 a side frame member, 4 the stationary section of a jamb structure 5, 6 the slideable section of the latter, 7 the lower sash, 8 the upper sash, 9 a vertically movable sustaining weight within structure 5, 10 and 11 a pair of spaced guide strips which extend from member 2 to sill 1 and are secured to member 3, 12 one of the slides of the upper pair of slides, 13 one of the slides of the lower pair of slides, and 14 a flexible sustaining member, such as a sash cord or chain which is common to the slides 12, 13 and coacts with the sustaining weight 9.

The frame member 3 is formed lengthwise of its inner face with a groove 15 conforming in contour to the shape of jamb section 4. The latter is arranged in groove 15 and secured to member 3 by holdfast devices 16. The section 4 is formed with a pair of oppositely inclined parts 17, 18 merging into each other at their inner sides and also merge at their outer sides into a pair of spaced parallel straight parts 19, 20 respectively which terminate into a pair of spaced parallel channel-shaped parts 21, 22 respectively arranged within section 4 and opposing the inner faces of the parts 19, 20 respectively. The parts 19, 20, 21 and 22 of section 4 are flush with the grooved face of member 3.

The slideable jamb section 6 includes a pair of oppositely inclined parts 22', 23 which are oppositely disposed with respect to the parts 17, 18 of the section 4. The parts 22', 23 at their outer sides merge into a pair of spaced parallel straight parts 24, 25 which slidably extend into the channel-shaped parts 21, 22 respectively of the section 4. The section 6 extends outwardly from the section 4 and the parts 22', 23 thereof at its inner sides merge into an extension 26 which constitutes a parting bead. The parting bead 26 is common to the slides 12, 13 and also common to the major portion of the length of one side of the upper and lower sashes. The extension 26 includes a front 27 and a pair of sides 28, 29. The side 28 extends from part 22' and the side 29 from part 23. The upper portion of side 28 is of channel-shaped contour as at 30 and opens outwardly at right angles to side 29. The lower portion of side 28 is straight and disposed outwardly at right angles to part 22'. The lower portion of side 29 is of channel-shaped contour, as at 31 and opens outwardly at right angles to side 28. The upper portion of side 29 is straight and disposed outwardly at right angles to part 23. Secured to the inner face of the parts 22', 23 at the upper portions thereof is the closed front of a vertically disposed stationary channel-shaped element 32 which extends from the top

and terminates at the lower end of the channel-shaped portion 30. The element 32 is open at its top, bottom and rear. Supported by and arranged at the upper end of element 32 is a pulley 33 which extends into the channel-shaped portion 30. Supported by and arranged at the lower end of element 32 is a pulley 34 which extends into the channel-shaped portions 30, 31 are oppositely disposed and provide a pair of guide channels, one for that portion 14' of the sustaining member 14 which associates with the upper sash 8 and the other for that portion 14'' of the sustaining member 14 which associates with the lower sash 7. The portions 14, 14'' of the member 14 pass over the tops of the pulleys 33, 34 respectively. The pulley 33 is of greater diameter than pulley 34. The sustaining weight 9 carries a pulley 35 around the bottom of which passes the member 14.

The sustaining weight 9 straddles the element 32 during the elevating and lowering movement thereof. The jamb structure 5 is formed with openings 36, 37 respectively for the passage of the pulleys 33, 34.

The section 6 of the jamb structure 5 is spring controlled by a pair of adjustable members 38, 39 carrying coiled springs 40 which abut the inner face of said section. The members 38 and 39 are arranged respectively within the upper and lower ends of and extend through the section 6 of jamb structure 5. The top frame 2 is formed with a mortise 41 into which extends the upper end of jamb structure 5. The mortise 41 provides a clearance for the outer end of member 38. The lower end of jamb structure 5 is mounted upon a plate 42 countersunk in sill 1.

The upper slides 12 are of like construction and oppositely disposed and each includes an oblong bar 43 having its outer face conforming in shape to part 22' of jamb structure section 6. The front face of bar 43 conforms in contour to the outer face of a side 44 of sash 8. The rear face of bar 43 is rabbeted as at 45 and mortised in its top edge as at 46. The upper end of rabbet 45 opens into mortise 46. The front face of the side 44 of sash 8 is rabbeted as at 47 and which registers with rabbet 45. The top edge of sash 8 is mortised as at 48 into which opens the rabbet 47. The mortise 48 normally aligns with the mortise 46. The bottoms of the mortises 46, 48 extend inwardly and incline downwardly from the front faces of the sash and bar. The manner in which the bottoms of the mortises are set up is as indicated at 49, Figure 8. The upper end portion of bar 43 is offset laterally as at 50. The width of bar 43 from the lower end of the offset 50 to the lower end of the bar is less than the width of parting bead 26. That part of bar 43 which is laterally offset is greater than the width of bead 26. The width of the top portion of sash 8 is reduced to provide shoulders 51, only one shown and which is overlapped by the lower end of offset 50. The height of bar 43 corresponds to that of the sash 8. The front face of sash 8 is grooved as at 52 and which forms a downward continuation of rabbet 47. The reducing of the width of the upper portion of the sash 8 provides for the sash to clear the parting bead 26. That part of the sash 8 below its upper portion of reduced width slides against the parting bead 26 when the upper slides are vertically shifted with the sash 8 in non-adjusted position.

Arranged in rabbets 45 and groove 52 is a pivoted latching member 53 having a hooked-shaped upper end 54 for overlapping the bottoms

of the mortises 46, 48 for latching the sash 8 to the slide 12 to prevent it from pivoting with respect to the latter until the member 53 is swung clear of the mortises 46, 48. Fixedly secured to the sash 8 and mounted in the portion of bar 43 of greatest width is a pivot 54 for sash 8, whereby when the latching member 53 is released the sash 8 can pivot to various angles with respect to its slides. Fixed to the sash 8 and to the member 53 is a hinge element 55 for the latter.

The slides 12 of the upper pair of slides, only one shown, are attached to the sustaining members 14, only one shown, and with respect to the bar 43 of each upper slide the outer end of portion 14' of a member 14 is anchored, as at 56 to said bar 43. The portion 14' extends into a curved groove 57 formed in the front of the wide portion of the bar 43. The groove 57 opens into a pocket 57' in bar 43 and within the lower part of the wide portion of the pocket is arranged the anchoring means 56.

For the purpose of maintaining the sash 8 at various angles with respect to the slides 12, the top frame member 2 is provided with a recess 58 in its bottom face. Arranged in recess 58 is a keeper 59 capable of being engaged by the member 53 to hold the sash 8 at various angles with respect to the slides, the position depending upon the position of the slides. See dotted line showing, Figure 10, illustrating the coacting of member 53 with respect to keeper 59 for holding sash 8 at the desired angular position. Carried by guide strip 10 is a stop 60 of any suitable form and which acts to prevent the pivoting of sash 8 on its slides whenever the bottom rail 61 of sash 8 is below the stop. The stops 60 on guide strips 10 are arranged in the path of movement of the outward swing of sash 8 on its pivots. The stops 60 may be located at any point desired on strips 10. The manner of mounting the sash 8 upon the slides therefor permit of sash 8 being adjusted to various angular positions with respect to the slides and further permit of it being turned to inside-out position as shown in Figure 10.

The slides 13 of the lower pair of slides are of like construction and oppositely disposed. Each includes an oblong bar 61 having its lower portion formed with a lateral offset 62. The width of bar 61 from the upper end of the lateral offset 62 to the upper end of the bar is less than the width of the parting bead 26. That part of the bar 61 which is laterally offset is greater than the width of parting bead 26. The width of the lower portion of the lower sash 7 is reduced to provide its sides with shoulders 63 only one shown. The upper end of offset 62 opposes a shoulder 63. The reducing of the width of the lower portion of sash 7 further provides for the sash to clear the parting bead 26. That part of the sash 7 above its lower portion of reduced width slides against the parting bead when the lower slides are vertically shifted with the sash 7 in non-adjusted position. A pivot member 64 is secured to and projects from each side of sash 7 of the portion of reduced width of the latter. Each member 64 is mounted in the upper portion of a bar 61 and provides for pivotally suspending the sash 7 with respect to the slides thereof. One face of bar 61 opposes and is of the same contour as part 23 of section 6 of the jamb structure 5. The wide portion of the bar 61 in proximity to its lower end is formed with a pocket 65 and leading thereto is a curved groove 66 arranged at the lower corner of the front face of

the wide portion of bar 61. The portion 14" of member 14 passes through groove 66, extends into pocket 65 and is anchored to bar 61, as at 67.

The sash 7 is latched to slide 13, by a spring controlled latching means 68 and cannot swing relative to the slide until the means 68 is moved from engagement with bar 61.

The construction and arrangement of the slides 13 and sash 7 with respect to each other permit of the sash being angularly disposed with respect to the slides, and further permit of the sash 7 being turned inside-out as shown in Figure 10.

The strips 10 and 11 in connection with the extension 26 of the jamb structure provide each side frame member 3 with a pair of guide grooves or channels 69, 70, the former for the slides 12 and the latter for the slides 13.

Each side frame member 3 is formed of a pair of like oppositely disposed sections rabbeted on their inner side faces. The rabbeted portions of said sections register and provide the groove 15. The sections of member 3 are indicated at 3', 3" Figures 5 and 17. The section 3' has its non-rabbeted side face formed with a lengthwise groove 3''' for the reception of plaster to provide a seal between the side of the frame and the building or in other words to provide a moisture and windproof joint.

The lower slide 13 has an opening or socket 13', see Figure 15, to receive the latching means 68. The guide strip 11 is formed with an opening or socket 18', see Figure 10, to receive the latching means 68 for the purpose of latching the sash 7 at an angle with respect to the lower slide 13 in a manner as shown in Figure 15.

The stop 60 will function to retain the upper sash 8 at various angular positions with respect to the upper slide, because when the upper sash is free of connection with the top 2 of the frame and extended outwardly it will seat against stop 60 and in this connection see Figure 15.

When the upper sash 8 is extended at an angle with respect to the upper slides and at the same time coupled and suspended from the frame by the members 53, it cannot be swung downwardly on its pivots or the upper frame moved downwardly when a downward pressure is applied to the outer end of the sash. If pressure is applied to said outer end, a binding action will be had between the upper slide and the shiftable jamb sections and a binding action will be set up between the shiftable and stationary jamb sections. In this connection it will be stated that downward pressure applied to the outer end of the sash will in connection with the members 53 force the upper slides against the shiftable jamb sections whereby the rear portions of the latter will be caused to move inwardly into and bind against the rear portions of the stationary jamb sections. The positions of the sections of a jamb structure when in binding or wedging engagement, as well as the binding of the upper slide to a shiftable jamb section as shown in Figure 17. When the upper sash is extended and suspended from the top of the frame, the upper slide can only be lowered by pressure upon the inner end of the sash.

To cause the engagement of member 53 with element 58, the upper sash is slightly lowered, swinging slightly outwardly causing member 53 to be released from the upper slide. The upper sash is then moved vertically and as member 53 is carried by the sash 8 it is also elevated so its upper end will ride against the curved surface 53', Figure 16, and be directed to engage over ele-

ment 58 whereby the upper sash is detachably suspended from the top of the frame. The members 53 when coupled to the frame will be in the upward path of travel of the upper outer corners of the upper slide. It will be assumed that the upper sash and members 53 are in the dotted line position, Figure 10, or full line position, Figure 16, now if the upper slide is moved upwardly the upper outer corners thereof will 10 kick out members 53 and the hook ends of the latter will engage in the mortises 46, 48 whereby the upper slide and upper sash are latched together.

The stationary section 4 of a jamb structure 15 is formed at each end with a pair of oppositely inclined bendable extensions 4', 4" extending from the portions 17, 18 respectively thereof. The extensions project from the upper and lower ends of the sections of the side frame member 3. Each pair of extensions are overlapped and secured together in a manner as shown in Figure 18. The upper pair of extensions are secured to the lower face of sill 1 and the lower pair to the upper face of top 2.

25 The purpose of the extensions on the stationary jamb sections attached to the head and sill members of the frame is to prevent the frame from pulling apart at the corners where the stationary side jambs are nailed to the head and sill. The action of the spring controlled jambs and the wedging action of the upper sash when projected cause a horizontal expansive pressure between the two stationary jamb sections, said jambs depending on the extensions which are attached to the top and bottom of the frame to receive sufficient strength to withstand the horizontal thrust set up by the wedging action of the upper sash, when said upper sash is held in any angular position by the binding action of the 30 shiftable jambs wedged against said stationary jambs.

Figure 12 shows a modified arrangement of pivot means for the sashes and it is illustrated 45 solely in connection with a lower sash, but it is to be understood that the pivot means to be presently referred to is also applicable to the upper sash. The pivot means consists of a hinge formed of two sections 71, 72 and a pintle or pivot 73 between said sections. The section 71 is fixed to the offset 62 of slide 13 and overlaps the sash 7. The section 72 is fixed to the sash 7 and overlaps the slide above offset 62. The width of the sections 71, 72 are such as to constitute weather-stripping means at the lower portion of the lower slide and sash when the latter is closed. If used on the upper sash said sections would constitute a weather-stripping means at the upper portion of the upper sash and slide when the upper sash is closed.

55 With reference to Figure 13, it shows the upper sash 8 of a form corresponding to the lower sash and provided with a latching means 75 of the same form as the latching means 68. If the means 75 is employed for the upper sash, then guide strip 11 will be provided with an opening not shown, to receive the said means 75 to maintain the upper sash at an inclination as shown with respect to the lower sash, Figure 15, but with the upper sash extending outwardly 60 at an inclination from top to rear.

Figure 14 shows the shiftable jamb section 6 as provided with a roller bearing means 76 riding upon plate 42.

75 The lower face of the top 2 of the frame is provided with retaining strips 77 for the sashes

when moved to the upper end of the window opening.

Weather-stripplings are provided to be engaged by the sashes, which are indicated at 78, 79. A weather-strip 80 is carried by the top rail of the upper sash for interposition between such rail and the lower rail of the upper sash.

What I claim is:—

1. A window comprising opposed jambs provided with parting beads, upper and lower vertically movable slides spaced by said beads, upper and lower sashes pivotally supported from and bodily movable with said slides, means for normally latching the sashes to the slides, said sashes when released capable of being angularly adjusted 90 with respect to the slides and turned inside-out, and vertically movable sustaining means common to said slides having portions thereof traveling in said beads and connected to the upper slides in proximity to their upper ends and connected to the lower slides in proximity to their lower ends.

2. A window comprising opposed jambs provided with parting beads, upper and lower vertically movable slides spaced by said beads, upper and lower sashes pivotally supported from and bodily movable with said slides, means for normally latching the sashes to the slides, said sashes when released capable of being angularly adjusted 100 with respect to the slides and turned inside-out, vertically movable sustaining means common to said slides having portions thereof traveling in said beads and connected to the upper slides in proximity to their upper ends and connected to the lower slides in proximity to their lower ends, and said slides being grooved for receiving 105 said portions.

3. A window comprising opposed jambs provided with parting beads, upper and lower vertically movable slides spaced by said beads, upper and lower sashes pivotally supported from and bodily movable with said slides, means for normally latching the sashes to the slides, said sashes when released capable of being angularly adjusted 115 with respect to the slides and turned inside-out, vertically movable sustaining means common to said slides having portions thereof traveling in said beads and connected to the upper slides in proximity to their upper ends and connected to the lower slides in proximity to their lower ends, and said latching means for the upper sash adapted to engage with the window frame 120 for retaining the upper sash in angular relation with respect to said upper slides.

4. A window comprising opposed jambs provided with parting beads, upper and lower vertically movable slides spaced by said beads, upper and lower sashes pivotally supported from and bodily movable with said slides, means for normally latching the sashes to the slides, said sashes when released capable of being angularly adjusted 130 with respect to the slides and turned inside-out, vertically movable sustaining means common to said slides having portions thereof traveling in said beads and connected to the upper slides in proximity to their upper ends and connected to the lower slides in proximity to their lower ends, and stops to prevent the annular disposition of the upper sash until cleared by the bottom rail of the latter.

5. A window comprising opposed jambs provided with parting beads, upper and lower vertically movable slides spaced by said beads, upper and lower sashes pivotally supported from and bodily movable with said slides, means for nor- 135 140 145 150

- mainly latching the sashes to the slides, said sashes when released capable of being angularly adjusted with respect to the slides and turned inside-out, said upper slides being formed in proximity to their upper ends with pockets and grooves leading to said pockets, said lower slides being formed in proximity to their lower ends with pockets and grooves leading to said pockets, sustaining means common to said slides and having parts thereof traveling in said beads and extending through said grooves into said pockets, and means within said pockets for anchoring said parts to said slides. 5 80
6. A window comprising opposed jambs provided with parting beads, upper and lower vertically movable slides spaced by said beads, upper and lower sashes pivotally supported from and bodily movable with said slides, means for normally latching the sashes to the slides, said sashes when released capable of being angularly adjusted with respect to the slides and turned inside-out, said upper slides being formed in proximity to their upper ends with pockets and grooves leading to said pockets, said lower slides being formed in proximity to their lower ends with pockets and grooves leading to said pockets, sustaining means common to said slides and having parts thereof traveling in said beads and extending through said grooves into said pockets, and means within said pockets for anchoring said parts to said slides, and said latching means for the upper sash adapted to engage with the window frame for retaining the upper sash in angular relation with respect to said upper slides. 10 85
7. A window comprising opposed jambs provided with parting beads, upper and lower vertically movable slides spaced by said beads, upper and lower sashes pivotally supported from and bodily movable with said slides, means for normally latching the sashes to the slides, said sashes when released capable of being angularly adjusted with respect to the slides and turned inside-out, said upper slides being formed in proximity to their upper ends with pockets and grooves leading to said pockets, said lower slides being formed in proximity to their lower ends with pockets and grooves leading to said pockets, sustaining means common to said slides and having parts thereof traveling in said beads and extending through said grooves into said pockets, and means within said pockets for anchoring said parts to said slides, and stops to prevent the angular disposition of the upper sash until cleared by the bottom rail of the latter. 15 90
8. A window comprising opposed jambs provided with parting beads, upper and lower vertically movable slides spaced by said beads, upper and lower sashes pivotally supported from and bodily movable with said slides, means for normally latching the sashes to the slides, said sashes when released capable of being angularly adjusted with respect to the slides and turned inside-out, said upper slides being formed in proximity to their upper ends with pockets and grooves leading to said pockets, said lower slides being formed in proximity to their lower ends with pockets and grooves leading to said pockets, sustaining means common to said slides and having parts thereof traveling in said beads and extending through said grooves into said pockets, and means within said pockets for anchoring said parts to said slides, latching means for the upper sash adapted to engage with the window frame for retaining the upper sash in angular relation with respect to said upper slides, and stops to 20 95
9. A window comprising jamb structures, upper and lower slides traveling against said structures, upper and lower sashes pivotally supported from and bodily moving with said slides, means for normally latching the sashes to the slides, said sashes when released capable of being angularly adjusted with respect to the slides and turned inside-out, said slides being grooved and formed with pockets, said grooves being curved, the grooves in the upper slides being arranged in the front edges thereof and the grooves in the lower slides being arranged in the rear edges thereof, a pocket arranged within the outer side face of each slide at an end thereof, each groove opening at one end into a pocket, vertically movable sustaining means carried by the jamb structures, common to the slides and having portions thereof arranged in the grooves of the slides and extending into said pockets, and means within the pockets for anchoring said portions to the slides. 25 100
10. A window comprising jamb structures, upper and lower slides traveling against said structures, upper and lower sashes pivotally supported from and bodily moving with said slides, means for normally latching the sashes to the slides, said sashes when released capable of being angularly adjusted with respect to the slides and turned inside-out, said slides being grooved and formed with pockets, vertically movable sustaining means carried by the jamb structures, common to the slides and having portions thereof arranged in the grooves of the slides and extending into said pockets, means within the pockets for anchoring said portions to the slides, and said latching means for the upper sash adapted to engage within the inner face of the top of the window frame for retaining the upper sash in angular relation with respect to said upper slides. 30 105
11. A window comprising jamb structures, upper and lower slides traveling against said structures, upper and lower sashes pivotally supported from and bodily moving with said slides, means for normally latching the sashes to the slides, said sashes when released capable of being angularly adjusted with respect to the slides and turned inside-out, said slides being grooved and formed with pockets, the grooves of said slides leading to and opening at one end thereof into said pockets, vertically movable sustaining means carried by the jamb structures, common to the slides and having portions thereof arranged in the grooves of the slides and extending into said pockets, means within the pockets for anchoring said portions to the slides, and stops to prevent the angular disposition of the upper sash until cleared by the bottom rail of the latter. 35 110
12. A window comprising jamb structures, upper and lower slides traveling against said structures, upper and lower sashes pivotally supported from and bodily moving with said slides, means for normally latching the sashes to the slides, said sashes when released capable of being angularly adjusted with respect to the slides and turned inside-out, said slides being grooved and formed with pockets, vertically movable sustaining means carried by the jamb structures, common to the slides and having portions thereof arranged in the grooves of the slides and extending into said pockets, means within the pockets for anchoring said portions to the slides, said latching means for the upper sash adapted to 40 115
- 45 120

engage within the inner face of the top of the window frame for retaining the upper sash in angular relation with respect to said upper slides, and stops to prevent the angular disposition of the upper sash until cleared by the bottom rail of the latter.

13. A window comprising jamb structures, each including as a part thereof a parting bead formed with oppositely disposed channeled parts, vertically movable upper and lower slides bearing against said slidable sections adjacent said parts, upper and lower sashes pivotally supported from and bodily moving with said slides, means for normally latching the sashes to the slides, said sashes when released capable of being angularly adjusted with respect to the slides and turned inside-out, vertically movable sustaining means common to said slides and having stretches thereof arranged in the channels and extending into the upper portion of the upper slides and into the lower portion of the lower slides, and means within the upper end of the upper and lower end of the lower slides for anchoring the outer ends of said stretches therein.

14. A window comprising jamb structures, each including as a part thereof a parting bead formed with oppositely disposed channeled parts, vertically movable upper and lower slides bearing against said beads, upper and lower sashes pivotally supported from and bodily moving with said slides and having the major portion of the length of the sides thereof bearing against said beads, means for normally latching the sashes to the slides, said sashes when released capable of being angularly adjusted with respect to the slides and turned inside-out, vertically movable sustaining means common to said slides and having portions thereof arranged in the channels and extending into the upper portion of the upper slides and into the lower portion of the lower slides, means within said slides for anchoring said portions thereto, and said latching means for the upper sash adapted to engage into the top of the window frame for retaining the upper sash in angular relation with respect to said upper slides.

15. A window comprising a frame structure including parting beads, upper and lower vertically movable slides traveling against the sides of the structure and beads, upper and lower sashes pivotally supported from, bodily moving with the slides and having the major portion of the length of the sides thereof bearing against said beads, said sashes having the sides thereof formed with clearances relative to the beads to permit of the sashes being completely turned inside-out with respect to said slides and frame on the lowering of the upper slide and elevating of the lower slide, and means for supporting said sashes at an inclination with respect to the slides.

16. A window comprising a frame, jamb structures, each including a shiftable and a stationary section, an upper vertically movable slide, an upper sash pivotally connected to the slide, a pair of pivoted latching means between the said sash and slide, keepers at the top of the frame, said sash capable of being shifted at an inclination with respect to the slide with said pair of means in latching position, said pair of means when shifted from latching position engageable with the keepers when the sash is disposed at an inclination to suspend the sash and providing when downward pressure is applied to the outer end of the sash to cause a binding action between the slides and sections of the jamb structures to

prevent the downward shifting of the outer end of the sash and downward movement of the slides.

17. A window comprising a frame, jamb structures, each including a shiftable and a stationary section, an upper vertically movable slide, an upper sash pivotally connected to the slide, a pair of pivoted latching means between the said sash and slide, keepers at the top of the frame, said sash capable of being shifted at an inclination with respect to the slide with said pair of means in latching position, said pair of means when shifted from latching position engageable with the keepers when the sash is disposed at an inclination to suspend the sash and providing when downward pressure is applied to the outer end of the sash to cause a binding action between the slides and sections of the jamb structures to prevent the downward shifting of the outer end of the sash and downward movement of the slides, said pair of means when suspending the sash being arranged in the upper path of said slide, and said slide having means when said slide is moved upwardly for kicking off said pair of means from the keepers and for receiving the free end of said pair of means to latch the sash to the slide.

18. A window comprising jamb structures, each including as a part thereof a parting bead formed with oppositely disposed channeled parts, vertically movable upper and lower slides bearing against said beads, each of said slides having a portion of less width and a portion of greater width than the width of the slides, upper and lower sashes sliding against the beads and having parts of reduced width pivotally supported from the portions of greatest width of the slides, said sashes bodily moving with the slides, means for normally latching the sashes to the slides, said sashes when released capable of being angularly adjusted with respect to the slides and turned inside-out, vertically movable sustaining means common to said slides and having portions thereof arranged in the channels and extending into the upper portion of the upper slides and into the lower portion of the lower slides, means within said slides for anchoring said portions thereto, and stops to prevent the angular disposition of the upper sash until cleared by the bottom rail of the latter.

19. A window comprising a frame structure provided with parting beads, vertically movable upper and lower slides bearing on opposite sides of the beads and having portions of less width and portions of greater width than that of the beads, upper and lower sashes having parts of less width opposing the portions of greatest width of the slides and parts of greatest width bearing on opposite sides of the beads, means for pivotally connecting the said parts of less width to said portions of greatest width whereby the sashes will be pivotally suspended and supported from the slides and bodily movable with the latter, means for normally latching the sashes to the slides, vertically movable sustaining means for the slides, said sashes when released capable of being angularly adjusted with respect to the slides and turned inside-out.

20. A window comprising a frame structure provided with parting beads, vertically movable upper and lower slides bearing on opposite sides of the beads and having portions of less width and portions of greater width than that of the beads, upper and lower sashes having parts of less width opposing the portions of greatest width of the slides and parts of greatest width bearing on opposite sides of the beads, means for pivotally

connecting the said parts of less width to said portions of greatest width whereby the sashes will be pivotally suspended and supported from the slides and bodily movable with the latter, 5 means for normally latching the sashes to the slides, vertically movable sustaining means for the slides, said sashes when released capable of being angularly adjusted with respect to the slides and turned inside-out, and said frame structure at its top provided with means coacting with the latching means for the upper sash for sustaining the latter at an angle with respect to the upper slides. 10

21. A window comprising a frame, jamb structures, each including a shiftable and a stationary section, an upper vertically movable slide, an upper sash pivotally connected to the slide, a pair of pivoted latching means between the said sash and slide, keepers at the top of the frame, said sash capable of being shifted at an inclination with respect to the slide with said pair of means in latching position, said pair of means when shifted from latching position engageable with the keepers when the sash is disposed at an inclination to suspend the sash and providing when downward pressure is applied to the outer end of the sash to cause a binding action between the slides and sections of the jamb structures to prevent the downward shifting of the outer end of the sash and downward movement of the slides, said pair of means when suspending the sash being arranged in the upper path of said slide, said slide having means when said slide is moved upwardly for kicking off said pair of means from the keepers and for receiving the free end of said pair of means to latch the sash to the slide, and

said stationary jamb sections being provided at the ends thereof with extensions adapted to be anchored to the top and bottom of the frame to prevent the latter being pulled apart at corners thereof during the binding actions between the sections of the jamb structures. 80

22. A window comprising a frame, jamb structures, each including a shiftable and a stationary section, an upper vertically movable slide, an upper sash pivotally connected to the slide, a pair of pivoted latching means between the said sash and slide, keepers at the top of the frame, said sash capable of being shifted at an inclination with respect to the slide with said pair of means in latching position, said pair of means when shifted from latching position engageable with the keepers when the sash is disposed at an inclination to suspend the sash and providing when downward pressure is applied to the outer end of the sash to cause a binding action between the slides and sections of the jamb structures to prevent the downward shifting of the outer end of the sash and downward movement of the slides, said pair of means when suspending the sash being arranged in the upper path of said slide, 100 said slide having means when said slide is moved upwardly for kicking off said pair of means from the keepers and for receiving the free end of said pair of means to latch the sash to the slide, and said stationary jamb sections being provided at 105 their ends with extensions adapted to be anchored to the top and bottom of the frame to prevent corners of the latter being pulled apart during the binding action between the sections of the jamb structures.

HAMILTON T. REYNOLDS.
